FINGERNAIL CLIPPER OR THE LIKE

Bernard M. Rock, 1311 York St., Denver, Colo. 80206

Filed Feb. 18, 1971, Ser. No. 116,740

Term of patent 14 years

Int. Cl. D28—03

U.S. Cl. D86—10

FIG. 1

FIG. 2

FIG. 3

FIG. 4

FIG. 5

FIG. 6

FIG. 1 is a perspective view of a fingernail clipper, or the like embodying my new design;

FIG. 2 is a top plan view thereof;

FIG. 3 is a bottom plan view thereof;

FIG. 4 is a side elevation thereof as seen from the left of FIG. 2;

FIG. 5 is a front elevation view thereof; and

FIG. 6 is a rear elevation view thereof.

The righthand elevation of the fingernail clipper is a mirror image of the lefthand elevation illustrated in FIG. 4.

I claim:

The ornamental design for a fingernail clipper or the like, as shown and described.
